DAVYDD C. HUGHES, OF CHICAGO, ILLINOIS, ASSIGNOR, BY MESNE ASSIGNMENTS, TO JOHN B. HALL AND JOSEPH S. DUNCAN, OF CHICAGO, ILLINOIS.

RIBBON-INKER FOR PRINTING AND ADDRESSING MACHINES.

1,088,072.

Specification of Letters Patent.

Patented Feb. 24, 1914.

Application filed September 6, 1910. Serial No. 580,545.

To all whom it may concern:

Be it known that I, DAVYDD C. HUGHES, a citizen of the United States, and resident of Chicago, Cook county, Illinois, have invented certain new and useful Improvements in Ribbon-Inkers for Printing and Addressing Machines, of which the following is a full, clear, and exact description, such as will enable others skilled in the art to make and 10 use the same.

The object of my invention is to provide, in association with machines of this character, an inked ribbon or fabric for supplying the necessary ink for the printing operation, together with mechanism which will feed the ribbon to the printing mechanism, so that the ribbon, while having a considerable movement during each printing operation, will have a resultant, progressive movement at a comparatively slower rate of speed, but sufficient so that it will present a relatively different portion of its surface for each printing operation and which, in consequence of this manner of feeding the ribbon, will be very economical by reason of a reduction in the number and hence in the cost of ribbons for a given number of printed impressions.

A further object of my invention contemplates the provision of a ribbon inking mechanism, as above outlined, which will be entirely automatic in its operation and which will positively feed a relatively new portion of the ribbon surface to the printing mechanism during each printing operation until a given total length of ribbon has passed the printing position and then reverse the direction of feed of ribbon to repass it through the printing position.

A further object of my invention is to provide a ribbon inking mechanism which will be simple in construction and reliable in operation, and which will require practically no attention during the operation of the machine except when it is necessary to change the ribbon.

I will describe my invention by reference to the accompanying drawings in which:

Figure 1 is a longitudinal sectional view on line 1--1 of Fig. 2 of the forward portion of a printing machine and shows in association therewith a ribbon feed structure embodying my invention; Fig. 2 is a top plan view of the machine shown in Fig. 1, the paper feeding mechanism being removed

to expose the various parts in their relative operating positions; Fig. 3 is a perspective view of the ribbon inking mechanism; Fig. 4 is an enlarged sectional view on line 4--4 of Fig. 1 looking from above; Fig. 5 is an enlarged partial view in section on line 5--5 of Fig. 7; Fig. 6 is a partial vertical section on line 6--6 of Fig. 1; Fig. 7 is a sectional view on line 7--7 of Fig. 5; Fig. 8 is a sectional view on line 8--8 of Fig. 7; Fig. 9 is 65 a sectional view on line 9--9 of Fig. 4 showing the cams which determine fractional lengths of advance and retraction of the ribbon; Fig. 10 is a perspective view of one of said cams; Fig. 11 is a sectional view on line 11--11 of Fig. 1. Fig. 12 is a sectional view on line 12--12 of Fig. 11; and Fig. 13 is a diagrammatic view of the conveyer mechanism and the ribbon driving chain.

Like parts will be referred to by similar 75 reference characters throughout the several views.

I have chosen to illustrate my invention in connection with a printing or addressing machine of the class used in the "Rogers 80 addressing system." In printing machines of this class a plurality of unit or individual type holders, each containing printing type characters, are stacked up in a magazine at the rear of the machine and from this 85 magazine they are withdrawn one by one at timed intervals by a conveyer and passed through the printing mechanism. A piece of paper or other printable material is passed through the printing mechanism simultaneously with a type holder and the printing mechanism presses the paper and type holder together in order to produce a printed impression upon said paper. The type characters which are carried by the type holders 90 are usually made similar to the ordinary typewriter type, the reason for this being that it is desirable to have the impressions on the paper resemble typewritten impressions. It is essential then, in order to obtain the "ribbon effect," which is characteristic of the ordinary typewriter impressions, to interpose or intervene an inked ribbon between the face of the type and the paper upon which the impression is to be made so 105 that when the paper and type holders pass through the printing mechanism the type will print through the ribbon and thereby make an impression similar to that made by a typewriter. I have therefore provided a 110

ribbon and mechanism associated with the machine adapted to feed the ribbon through the printing mechanism in a proper manner to supply the necessary ink for the printing operation. I therefore interpose an inked ribbon between the paper and the type holders as they pass through the printing mechanism and provide mechanism for properly feeding the ribbon.

10 In order that an understanding of the entire machine may be had, I will describe the various operating mechanisms and their relation to each other in the following order: the frame, the magazine, the conveyer, 15 the paper feed mechanism, the drawer or receptacle for discharged type plates, the ribbon inking mechanism.

The frame.—Referring more particularly to Figs. 1 and 2. Since all of the mechanisms which make up the complete machine must necessarily be maintained in position in proper operative relation to each other, I have provided a frame for supporting these various parts. This frame comprises two 25 side members 1 arranged parallel and rigidly secured together but spaced apart to afford a strong, substantial, supporting structure. The side members are preferably of cast metal and of suitable form to accommodate the operating mechanisms and at the same time render the machine as light in weight as possible. The magazine 2 is vertically disposed at the rear end of the frame. In this magazine a stock of individual type 30 holders are placed for removal therefrom one at a time by the conveyer mechanism. The conveyer mechanism extends substantially the entire length of the frame along the upper portion thereof and comprises a 35 pair of endless sprocket chains which are carried by suitable sprocket wheels disposed at each end of the frame. The printing mechanism is located at the forward end of the frame and is adapted to receive type 40 plates from the conveyer mechanism and press them into engagement with the pieces of paper also fed thereto, and then discharge both paper and type holders, the type holders being directed downwardly into a comparatively 45 long, narrow drawer while the paper is discharged into a temporary receptacle placed in front of the machine. The paper feed mechanism is mounted in a separate carriage pivoted about midway of the 50 length of the framework at the upper portion thereof. It lies above the path of the type holders through the machine and at the "intake" side of the printing mechanism in position to feed thereto the printable material upon which imprints are to be made. The ribbon for supplying the necessary ink for the printing operations is stretched preferably parallel to the path of type holders and between two reels or holders, one of 55 which is located at the upper portion of the

framework between the magazine and the printing mechanism, and the other of which is carried by an extension at the forward end of the frame.

The type holder magazine.—As previously stated, the type holder magazine 2 is mounted in a vertical upstanding position at the rear end of the framework. In this magazine a stack of individual type holders 3 are placed and by which they are maintained in condition to be extracted or removed from the lower end thereof one by one and carried along the upper portion of the framework by the conveyer mechanism. It is comprised of two upstanding side plates 2' (Figs. 1 and 2) between which the type holders are arranged in stacked order. These plates have hinged flanges which retain the type holders in a vertical stack in the magazine.

The conveyer mechanism.—The conveyer mechanism extends substantially the entire length of the frame. It comprises a pair of endless chains 4 arranged in parallel relation and carried by sprocket wheels at each end of the frame. The forward sprockets 5 are carried upon a shaft 6 journaled in suitable bearings 7 in the forward end of the frame, as shown in Figs. 2 and 4. The rear sprocket wheels are not shown. However, they constitute a part of the Rogers machine and need not be particularly described except to say that they are mounted upon a shaft journaled in suitable bearings at the rear end of the framework in a manner similar to the forward sprockets. For the purpose of an understanding thereof, I have indicated diagrammatically in Fig. 13 the conveyer chains and the forward and rear sprockets upon which the chains are carried. In this view, 4 indicates one of the endless chains while 5 indicates one of the forward sprockets and 5' a rear sprocket mounted upon a shaft 8. From the shaft 8 the ribbon inking mechanism receives its motion through the medium of a sprocket chain 9 as will be hereinafter described. The upper sides of the conveyer chains move in grooves or channels 10—10 in the upper face of a guide or bed plate 11 which is disposed along the upper edges of the frame members 1 and which extends substantially the length of the conveyer mechanism, as clearly shown in Figs. 1 and 6. Each chain is provided with lugs 12 at intervals adapted to engage the lowermost type holders in the magazine and move them forward along the guide plate 11 to the forward end of the frame where they are received by the printing mechanism.

The printing mechanism.—This mechanism is disposed in the forward end of the frame. It comprises a large rotary drum 15 and an upper and smaller pressure roll 16 (Figs. 1, 2 and 4). The drum is coaxial 130

with the forward end of the conveyer and is mounted upon the shaft 6 with the upper portion of its surface substantially flush with the guide plate 11 so that the type 5 holders, as they leave the end of the guide plate, ride over the surface of the drum and drop down through a chute 17, the chute being located as is apparent at the delivery side of the printing mechanism in position 10 to receive the type holders therefrom. The upper or pressure roll 16 of the printing mechanism is disposed axially parallel with the drum and is rotatably mounted upon the swingable carriage 18 which spans or 15 bridges the upper forward portion of the framework, and which is adapted to swing upwardly on its pivots 20, in order to separate the drum and roll of the printing mechanism when desired. The lower drum receives 20 its motion from the conveyer chains 4. Suitable gear mechanism not shown is provided between the shaft 6 and the upper pressure roll 16 so that the drum and roll will be rotated in unison with the same peripheral speed. It might be well to mention 25 at this point that the machine may be driven either manually by a crank C on the outer end of the shaft 6, as shown in Fig. 2, or by an electric motor (not shown) which may be 30 connected with the rear shaft 8. It will thus be seen that by means of the printing mechanism the type holders and pieces of printable material, as they pass simultaneously therethrough, will be pressed into 35 intimate engagement between the drum and the pressure roll, and an impression will be made upon the printable material. This occurs periodically as the conveyer mechanism brings a type holder forward to the 40 printing mechanism and the paper feed mechanism simultaneously advances thereto a piece of printable material.

The paper feed mechanism is disposed above the path of the type holders through 45 the machine and adjacent to and at the "intake" side of the printing mechanism and in position to feed pieces of paper to the printing mechanism. It is adapted to periodically feed the paper in time to meet 50 the type holders upon their arrival at the printing mechanism so that the paper and type holders will pass together through the printing mechanism, the pieces of paper being above the type holders. The feed mechanism 55 is mounted upon the swingable carriage 18. It comprises a feed roll 23 disposed parallel to the pressure roll 16 of the printing mechanism, and a paper holding plate 24 having a ledge parallel with the 60 surface of the feed roll. A magazine having two angularly related floors 25 and 26 is associated with the feed mechanism for holding a pack of pieces of paper in proper position on the plate 24. The feed roll rotates 65 in unison with the pressure roll of the

printing mechanism and receives its motion through suitable intermediate gears (not shown). It is adapted to frictionally withdraw sheets of paper one at a time from the magazine and feed them diagonally downwardly along a guide plate 27 to the space between the roll and drum of the printing mechanism. At this point the pieces of paper meet the type holders and pass therewith through the printing mechanism.

It is essential in a machine of this character that the advance of the paper be controlled and timed so that it will meet the type holder at the proper time. This timing of the paper is controlled by means of stopping and releasing dogs 28. The periods of action and inaction of the dogs are controlled by means of a cam 29 mounted upon the shaft 6 and a system of levers 30 operated thereby, as shown in Figs. 1 and 4.

The drawer or receptacle for discharged type plates.—It will be noted by reference to Fig. 1 that the chute 17 is disposed at the delivery side of the printing mechanism in position to receive the discharged type plates 35 therefrom and direct them downwardly. A comparatively long, narrow receptacle or drawer 32 is suitably supported between the side members of the frame along the lower portion thereof. The front end of this drawer is disposed below the mouth of the chute 17 in position to receive the type holders 3 therefrom. As the type holders drop into the drawer they are engaged by a pusher mechanism 33 and pushed toward the rear end of the drawer in a manner to form a stack in the drawer. The drawer is removable from the machine so that it may be filed with its stack of type holders in a filing cabinet.

The ribbon inking mechanism.—In a machine of this character it would be possible to supply the type holders with ink at some point in their path through the machine and before they reach the printing mechanism, but if they were inked in this manner the "ribbon effect", which is desirable in the character of the work performed by the machine, could not be obtained. I therefore interpose an inked fabric or ribbon between the type holders and the pieces of paper at the printing mechanism in such a manner that the printing mechanism presses the type holder, the piece of paper and that portion of the ribbon which is in the printing position into intimate engagement, thereby causing the type to make their impression upon the paper through the ribbon. This ribbon 35 (Figs. 1 and 3) is disposed above the guide plate 11 and is substantially parallel with the path of the type holders through the machine in order that it will lie flat upon the printing faces of the type. It is stretched between two reels or holders 36 and 37 disposed on opposite sides of the

printing mechanism. For convenience of explanation I term the reel 36 the "pay-out" reel and the reel 37 the "take-up" reel. As shown in Fig. 5 the "pay-out" reel is mounted upon a shaft 39 journaled in a suitable bearing 40 formed in the gear casing 41. The gear casing has a shoulder 42 which rests upon the upper edge of one of the side members 1 of the frame and is securely clamped thereon by means of the bolt 43. It will be noted that the shaft 39 and its journal bearing 40 project laterally from the gear casing a proper distance to position the reel in proper alinement with the printing mechanism, the projecting end of the journal being strengthened by a web 44. The "pay-out" reel is rotatably mounted upon its shaft. It is, however, clamped between a collar 45 on the shaft and a thumb-nut 46 so that the reel will rotate with the shaft, the thumb-nut being screwed on the end of the shaft so as to permit the reel to be removed when it is desired to remove or change the ribbons. This reel is adapted to be positively driven by gear mechanism in either direction to pay out the ribbon or to wind it up on said reel, as will be hereinafter described.

The ribbon, as will be seen, is stretched through the printing mechanism and supported in position by a reel or holder 37 which for convenience I term a "take-up" reel, and which is mounted upon a shaft 47 carried in extensions 48 on the forward end of the frame. Since the "pay-out" reel alternately pays out and pulls back portions or lengths of ribbon, the "take-up" reel must wind up the ribbon which is paid out, but it also must respond to the action of the "pay-out" reel when the ribbon is being pulled back. While it would be possible to actuate the "take-up" reel by frictional driving mechanism or by spring mechanism in such a manner as to constantly tend to rotate the reel in one direction, but render it yieldable when the ribbon is being pulled back, I find that a spring actuating mechanism, contained within the reel, forms a simple and effective means of accomplishing this purpose. This spring actuating mechanism consists of a number of spiral sections or coils 49, as clearly shown in Figs. 11 and 12, the outer end of one coil being secured to the inner end of the adjacent coil by means of cup-shaped members 50 and their hubs 51 so as to constitute a series and afford uniform tension throughout a wide range of rotation of the reel. The several coils of the series are all contained within the closed hollow casing 52 and one of the series is anchored at 53 to this casing.

The casing is prevented from rotating by means of a lathe-dog 54 clamped on the hub 55 of the casing, the end of this dog being secured by means of the bolt 56 to a depend-

ing bail 48' on the ends of the extensions 48. The other end of the series is pinned at 57 to the hub of the gear 58. This pin is connected through the pinion and spur gear 59 to a toothed sleeve 59', the pinion and spur gear being carried by a small stud bolt 52' mounted on the side of the casing 52. The toothed sleeve 59' is fastened by means of its flanges 59² to the side of the reel. The reel itself is hollow and has flanges 37' at its ends for holding the ribbon on the reel as shown. The function of this mechanism is to maintain the ribbon in its properly stretched, flat condition during the operation of the machine, and while I have shown a multiple spiral spring to uniformly tension the ribbon throughout a large number of rotations of the reel thereby adapting it to a considerable length of ribbon, it is obvious that any other mechanism suitable for the purpose may be used.

It is obvious that since the ribbon is pressed between a type holder and a piece of paper during their transit through the printing mechanism, its length of movement depends upon substantially the length of the lines of type in the type holder, and that it must move at the same speed as the type and paper so as not to smudge the impression upon the paper. It is furthermore desirable that the ribbon present a different or relatively new portion of its surface to each type holder as it passes through the machine so that the type will make a clear and uniform impression upon the paper at each operation. Another desirable thing in a machine of this character is that the ribbon mechanism be entirely automatic in its operation and require practically no attention on the part of the operator until it becomes necessary to substitute a new ribbon for a used or worn out one. From a standpoint of economy it is advantageous to use all the available inked surface of the ribbon. I have therefore provided a mechanism which is entirely automatic in its operation and which feeds the ribbon in such a manner that it will be completely used up and no portion of it will be wasted and which also enables me to obtain all of these advantages with a simple and reliable structure. By this mechanism the ribbon is fed through the printing mechanism simultaneously with and at the same speed as the type holders and pieces of paper while they are in transit through the printing mechanism. When the type holders have passed the printing mechanism the ribbon is retracted to a greater or lesser amount so that, while for each printing operation the ribbon is advanced and retracted a considerable distance, the total progressive movement from one reel to the other is comparatively small, but it is sufficient, however, to present a relatively different ribbon surface for each printing operation. In fact,

the progressive movement of the ribbon is equal to the difference between the advance and retract of the ribbon and this, of course, may be made any desired amount to suit the 5 requirements of the particular machine or of the work which is performed thereby. I have also arranged this mechanism so that when a given total length of ribbon has been transferred from one reel to the other it 10 automatically changes the relative fractional lengths of advance and retract and retransfers the ribbon back to the first reel. This operation will continue while the machine is in operation until the ribbon is completely 15 used up or worn out, and of course a new ribbon may then be substituted.

As previously stated, the "pay-out" reel 36 is positively driven in either direction by means of the train of gears contained in the 20 casing 41. The gearing in this casing is divided into two sets or trains A and B for driving the reel shaft 39 and they are suitably journaled in bearings within the casing to maintain them in their proper relation. The casing completely incloses and 25 protects the gearing. It is divided, however, to permit access to the interior thereof. The train A comprises the intermeshing spur gears *a* and *b* and the train B comprises gears *c*, *d*, *e*, *f* and *g*, the two upper gears *h* and *i* being common to both trains. The gears *e* and *d* are connected together by the shaft *k*.

As previously stated, the ribbon inking 35 mechanism receives its motion through the medium of the sprocket chain 9 which extends to the rear shaft 8 of the conveyer mechanism and is driven thereby. This chain drives a sprocket 60 carried on the 40 outer end of a shaft 61 journaled in a projecting bearing 62 of the frame member 1 and in a suitable bearing formed by the casing 41. Upon this shaft are freely mounted the gears *b* and *g* of the trains A 45 and B respectively, and between said gears is a reversible clutch mechanism comprising the two outer members 63 and 64, associated with the gears *b* and *g* respectively, and the shiftable intermediate member 65. The intermediate member 65 is splined to rotate 50 with, but to slide upon, the shaft into engagement with either one of the outer clutch members, as clearly shown in Figs. 5 and 7. The intermediate member is shifted into engagement with either one of the outer clutch members by means of a rock shaft 66 55 journaled in a suitable bearing in the lower end of the casing and carrying a bifurcated arm 67 which straddles the intermediate member and has short pins on its ends operating in a groove 68 in said member which provides operable connection between the arm and the intermediate member. The shaft 66 is rocked in its bearings to shift the 60 clutch member by means of a bell crank

lever 68 pivoted upon a stud shaft 69 depending from the under side of the guide plate 11. One arm of this bell crank lever is connected by means of a link 70 to the rocker arm 71 on said shaft 66. The other arm 72 of the bell crank lever carries a roller 73. This roller rides upon one or the other of two cams 74 and 75, depending upon whichever cam is brought into engagement with it. By referring particularly to Figs. 75 3 and 4, it will be noted that these cams are mounted upon a hub 90 which is splined to rotate with but to slide or shift upon the shaft 91 which is journaled in a depending portion 92 of the framework. The shaft 91 receives its motion to drive the hub, from the shaft 6 of the rotary drum, through the medium of a train of intermeshing gears 93. The hub is shifted on the shaft by a lever 79, the short arm of which is bifurcated so as to straddle the hub. The bifurcations of said short arm have pins which ride in a groove 94 and permit the hub to turn but at the same time to furnish an operative connection by which the hub may be shifted. In this manner one or the other of the cams is brought into engagement with the roller 73. 85 90

As I have previously mentioned, a fractional length of the ribbon is advanced while a type holder and a piece of paper are in transit through the printing mechanism and a greater or lesser fractional length is retracted after the printing operation in order to give the ribbon a progressive movement equal to the difference between the fractional lengths of advance and retract. The cams 74 and 75 constitute the means of determining the relative fractional lengths of advance and retract of the ribbon. Since the bell crank lever 68 is swung on its pivot 100 by the cams it shifts the clutch mechanism associated with the two trains of gears A and B. It will be seen that by making these cams of different lengths, the clutch mechanism will be operatively connected with one 105 of its outer members for a longer period of time than with its other outer member, and the consequence is that the "pay-out" reel will be accordingly rotated to "pay-out" more or less ribbon than it retracts. The gear 110 wheels *e* and *f* are mounted upon and drive a long shaft 75' journaled in suitable bearings in the side member 1 of the frame and in the gear casing 41. The free end of this shaft has screw threads, along which operates a traveling nut 76. Like the "pay-out" reel, this shaft is driven in either direction depending upon whichever one of the trains of gears A and B is operatively connected with the clutch. In other words, if the 115 clutch member 63 is connected to the intermediate member, thereof, the shaft 75' is driven in one direction through the medium of train A, shaft *k* and back through train B, while if clutch member 64 is in en- 120 125 130

gagement with the intermediate member the shaft 75' is driven in the opposite direction directly through gears g and f of train B. It is clearly seen then that, due to the screw 5 threads on the shaft, the nut 76 is given a movement upon its shaft similar to the movement of the ribbon, that is, it reciprocates on the shaft in a manner corresponding to the advance and retract of the ribbon, and like the ribbon its movement in one direction is greater or lesser than that in the other direction which, in consequence, gives it a progressive movement on the shaft. This nut constitutes the means for determining the total length of the ribbon which is transferred from one reel to the other. In this case the mechanism is so adjusted that the nut will travel progressively in either direction a distance corresponding 10 substantially to the total length of the ribbon. The nut controls the cam mechanism which changes the relative fractional lengths of advance and retract of the ribbon so that when it reaches substantially the end of its 15 progressive movement from one reel to the other the direction of the resultant movement of the ribbon is reversed. It operates between substantially the limits indicated by dotted lines 78 and when it reaches either 20 one of these limits it throws the lever 79 against one or the other of the cushioned stops 80 and this lever in turn shifts one or the other of the cams 74 and 75 into engagement with the roller 73. (Figs. 3, 7 25 and 8). Between the free end 81 of the lever 79 and the traveling nut 76 is a "throwover" mechanism which comprises two levers 82 and 83 pivoted upon a stud shaft 84 on the under side of the guide 30 plate 11. The free end of arm 82 has a pin and slot connection with the traveling nut while the free end of the lever 83 is connected by a link 85 to the end 81 of lever 79. A spiral spring 86 is connected between 35 pins 87 on said levers and places the levers under tension in a manner which tends to collapse or bring them together. As the traveling nut moves along its shaft it swings the lever 82 on its pivot until the spring 86 40 passes the pivotal center of the arms. The spring snaps over the lever 83 and the two arms assume similar angular positions on the opposite side of their pivotal centers, as shown in dotted lines in Fig. 7. This action 45 throws the lever 79 against the corresponding opposite stop 80 and causes one of the cams to be moved out of engagement and the other into engagement with the roller 73 of bell crank lever 68. As soon as this 50 happens the cams change the relation of the fractional lengths of advance and retract of the ribbon, as previously stated, and the ribbon starts its progressive movement in the return direction. The traveling nut correspondingly imitates the movement of the 55

ribbon until it reaches its other limit of travel and again repeats its operation.

Referring now more particularly to Fig. 3, I will describe the operation of the ribbon feed mechanism. In the printing machine 70 which I have described and shown in this application, the conveyer mechanism and the rotary drum of the printing mechanism are so proportioned with relation to each other that a type holder is brought forward 75 to the printing mechanism with each complete rotation of the drum, that is one type holder per revolution of the drum. This, however, depends upon the number and position of the lugs on the conveyer chains. Thus the necessity for one cycle of advance 80 and retract of the ribbon for each revolution of the drum is apparent. Furthermore, it is apparent that the advance or forward movement of the ribbon must be coincident 85 with and at the same speed as the passage of a type holder through the printing mechanism. I have so constructed the cams and proportioned their driving gear train 93 that the clutch will be operated once for 90 each revolution of the drum. The cams and the lugs on the conveyer chains are related to each other in such a manner that the cams operate the clutch to advance the ribbon simultaneously with the passage of a type 95 holder and piece of paper through the printing mechanism. The train of gears A associated with the "pay-out" reel I term for convenience the "advance" train. This train is so proportioned that it will operate 100 the reel 36 and pay out the ribbon at the same speed as that of the type holders when passing through the printing mechanism so as not to blur the impression on the paper which would obviously be the case if relative 105 movement existed between the type holder and the ribbon. The length of the cam surfaces bears a definite relation to the train of gears B which for convenience I term the "retract" train. To be more specific, the 110 cam 74 or "long" cam is of such length that it maintains the "pay-out" gear train in operation long enough to pay out or advance a slightly greater fractional length of ribbon than is retracted by the "retract" train. 115 Likewise the cam 75 or "short" cam is of such length that it causes the "pay-out" train to advance a lesser fractional length of ribbon than is retracted by the "retract" train. Thus it is apparent that when the cam 120 74 is in operation the ribbon is advanced a greater fractional length than it is retracted and in consequence the ribbon is given a resultant progressive movement which gradually transfers it to the "take-up" reel. 125 Consistent with this explanation, the shorter cam, when in operation, causes a lesser fractional length of ribbon to be advanced than is retracted and in consequence the ribbon is given a resultant progressive movement 130

which winds it up on the "pay-out" reel and, as I have previously mentioned, the traveling nut operates to bring one or the other of the cams into engagement at each 5 end of the given total length of ribbon.

In the particular printing machine herein shown, the interval between the arrival of type holders to the printing mechanism is considerably longer than the time actually 10 consumed in the passage of a type holder through the printing mechanism. It is advisable, therefore, to bring about the retraction of the ribbon at a much slower rate than the advance thereof for the reason that 15 it eliminates to a great extent the wear and tear on the mechanism which would be incident to comparatively high speeds. Accordingly, I have proportioned the B train or "retract" train of gears so that substantially 20 all of the time between the end of the passage of one type holder through the printing mechanism and the arrival of the next type holder is consumed in retracting the ribbon. This method of operation gives 25 the ribbon a chance to become settled or composed, so to speak, due to the action of the spring actuated "take-up" reel and thereby be in complete readiness for the next advance.

Assuming that the various parts are in 30 the condition shown in Fig. 3, the traveling nut is correspondingly in position at one end of its range of travel, indicated by the dotted lines 78 in Fig. 7, and the cam 75 is in 35 operative relation to the roller 73 of bell crank lever 68. As each type holder and piece of paper arrive at the printing mechanism, the cam 75 simultaneously swings the bell crank lever 68 on its pivot and throws 40 the intermediate clutch member in operative relation to the train of gears A and this train of gears advances the necessary fractional length of ribbon at the same speed as the type holder during the passage thereof 45 through the printing mechanism. After the type holder and piece of paper passes the printing mechanism the cam 75 permits the spring 34 to return the bell crank lever and throw the intermediate clutch member 50 into operative connection with the train of gears B, and this gear train retracts a greater fractional length of the ribbon at a slower speed and in consequence a length of ribbon equal to the difference between the 55 lengths of advance and retract is wound upon the "pay-out" reel. This operation continues until substantially the total length of ribbon is wound upon the "pay-out" reel, and the traveling nut reaches the right hand 60 limit of travel as shown in Fig. 7 and throws over the lever 79 to the positions shown in dotted lines, whereupon the cam 74 is shifted into engagement with the roller 73 and causes, during its operation, a greater fractional 65 length of ribbon to be advanced than

is retracted, and as a result the ribbon is given a resultant, progressive movement which winds it up on the "take-up" reel. The ribbon is thus transferred from one reel to the other until it is worn out. 70

The structure which I have shown in the drawings constitutes one embodiment of my invention. It is particularly designed and adapted for association with printing machines of the class used in the "Rogers system." It is evident, however, that my invention may be embodied in various structures designed to suit the requirements of the particular machines with which they are associated without departing from the spirit 75 thereof. 80

I claim:

1. In a printing mechanism the combination with pressure rolls, of means by which printable material and impression carrying forms are simultaneously passed therebetween at timed intervals, an inked ribbon interposed between said printable material and said forms, holders for said ribbon maintaining it in relative position, 85 and mechanism associated with said holders for transferring said ribbon from one holder to the other by a reciprocating, progressive movement for causing the ribbon to present a relatively new inked surface for each 90 printing operation, said mechanism moving the ribbon forward synchronously with the form and material during the impression operation. 95

2. In a printing mechanism the combination with pressure rolls, means by which type holders and pieces of printable material are simultaneously moved forward into printing position at timed intervals between said pressure rolls, an inked ribbon 100 interposed between a type holder and a piece of printable material at the printing position, holders for said ribbon, and mechanism associated therewith for advancing a portion of said ribbon during each impression operation of the machine synchronously with the holder and material and for retracting a lesser portion thereof after each printing operation to cause said ribbon to be progressively transferred from one holder 105 to the other, and mechanism adjusted to change the length relation of the advance and retract portions of said ribbon after a predetermined total length of ribbon has 110 been passed through the printing position, thereby causing said ribbon to be retransferred to the original holder. 115

3. The combination of a printing machine in which type holders and pieces of paper are brought forward into printing position 120 at timed intervals, of an inking ribbon interposed between a type holder and a piece of paper at the printing position, a holder for said ribbon disposed on each side of said printing position for supporting the ribbon 125 130

- relatively thereto, mechanism for advancing a given fractional length of ribbon during the impression operation and at the same speed as the type holder and paper, and for 5 retracting a greater or lesser fractional length of ribbon during the intervals between printing operations and at a comparatively lower speed, thereby imparting a resultant, progressive movement to the 10 ribbon from one holder to the other, and mechanism for reversing the direction of progressive movement of the ribbon after a predetermined total length of ribbon has passed the printing position.
- 15 4. The combination with a printing machine in which type plates and pieces of printable material are passed forward into printing position at definite intervals and at a given speed, of an inked ribbon interposed between the type plates and pieces of 20 printable material at the printing position, holders for said ribbon, one positioned on each side of the printing position, and mechanism associated therewith for advancing 25 definite fractional lengths of said ribbon through the printing position at the same speed as the type plate and printable material and for retracting different fractional lengths of ribbon at a comparatively lower 30 speed so that a total length of ribbon is resultantly transferred from one holder to the other equal to the total differences between the fractional lengths of advance and retractive movements.
- 35 5. The combination of a printing machine in which type holders and pieces of paper are brought together into printing position at regular periods, of an inked ribbon interposed between the paper and type holders at 40 the printing position, a holder for said ribbon on each side of said printing position for maintaining said ribbon in operative relation thereto, mechanism for advancing synchronously with the paper and type 45 holder a fractional length of ribbon through the printing position substantially equal to the length of printed impression made on said paper, and for retracting a lesser fractional length thereof after the printing operation so that said ribbon is given an intermittent progressive movement to transfer it from the one holder to the other, and mechanism, operable when a predetermined total 50 length of ribbon has been transferred in one direction, for automatically changing the fractional length relations of advance and retract to reverse the direction of progressive movement of the ribbon for retransferring it to the original holder whereby said 55 ribbon presents a relatively new inked surface for each printing operation.
- 60 6. A printing machine having a magazine in which a plurality of type holders are contained and a magazine in which a plurality of pieces of paper are contained, pressure 65 rolls in the printing position for pressing a piece of paper upon a type holder, and mechanisms for simultaneously passing type holders and pieces of paper between said rolls at timed intervals, in combination with an 70 inked ribbon intervened between a piece of paper and a type holder at the printing position, mechanism for advancing a fractional length of said ribbon between said pressure rolls simultaneously with the passage there- 75 between of a type holder and a piece of paper, and for retracting a lesser fractional length of ribbon after the passage of said type holder and piece of paper, thereby causing the ribbon to intermittently travel 80 progressively through the printing position so as to present a relatively new, inked surface for each printing operation, and mechanism for automatically changing the fractional lengths of advance and retraction of 85 the ribbon after a predetermined total length of ribbon has passed the printing position to reverse the direction of progressive travel of the ribbon.
- 90 7. A printing machine having a magazine in which a plurality of type holders are contained and a magazine in which a plurality of pieces of paper are contained, pressure rolls in the printing position for pressing a piece of paper upon a type holder and mechanism for automatically passing type 95 holders and pieces of paper between said rolls at timed intervals, in combination with an inked ribbon intervened between a piece 100 of paper and a type holder at the printing position, mechanism for advancing a fractional length of said ribbon between said pressure rolls simultaneously with the passage therebetween of a type holder and a piece of paper, and for retracting a lesser 105 fractional length of ribbon during the time interval between the passage of successive type holders and pieces of paper, thereby causing the ribbon to intermittently travel 110 progressively through the printing position so as to present a relatively new, inked surface for each printing operation, and mechanism for automatically changing the fractional lengths of advance and retraction of 115 the ribbon after a predetermined total length of ribbon has passed the printing position to reverse the direction of progressive travel of the ribbon.
- 120 8. The combination with a printing machine in which printing type holders and printable material are simultaneously passed through the printing position of said machine at timed intervals, of an inked ribbon interposed between the type holders and printable material at the printing position, a supply reel for said ribbon disposed at one side of said printing position, and an automatic "take-up" reel disposed at the opposite side of the printing position, both maintaining 125 said ribbon in proper relation to the 130

- printing position, variable speed mechanism operating said supply reel for passing a fractional length of ribbon through the printing position simultaneously with the 5 passage therethrough of a type holder and a piece of printable material and at the same speed, and for retracting a lesser fractional length of ribbon during the time interval between the passage of type holders and print- 10 able material and at a relatively slower speed, thereby periodically transferring the resultant fractional lengths of said ribbon from the "supply" reel to the "take-up" reel, and mechanism adjusted to operate when a 15 given total length of ribbon has been transferred for increasing the fractional length of retraction of the ribbon to transfer the ribbon to the "supply" reel.
9. A printing machine wherein type plates 20 and pieces of paper are simultaneously passed through the printing mechanism of the machine at timed intervals, in combination with the inked ribbon interposed between the type holders and the pieces of paper at 25 the printing position, a "pay-out" holder and a "take-up" holder for the ribbon disposed on opposite sides of the printing position, gear mechanism for positively actuating said "pay-out" reel to advance fractional lengths of ribbon simultaneously with the passage of corresponding type holders and pieces of paper through the printing position and for retracting fractional lengths of ribbon during the intervals between the 30 printing operations, cams controlling said gear mechanism and adjusted for different fractional length relation of advance and retract to impart to said ribbon a resultant, progressive movement in either direction, a 35 member associated with and operated by said gear mechanism and having a movement corresponding to that of the ribbon, and means operated by said member after it has moved progressively a predetermined 40 amount in one direction for shifting said cams to change the relative lengths of advance and retract and thereby reverse the progressive travel of the ribbon.
10. A printing machine having a printing 45 mechanism through which pieces of paper and type plates pass together, in combination with a "take-up" reel and a "pay-out" reel arranged on opposite sides of said printing mechanism and having an inked ribbon 50 extending therebetween and interposed between the paper and type plate, mechanism actuating said "take-up" reel and exerting a constant pull on the ribbon in the direction of movement of the paper and type 55 plates, and another mechanism operating in 60 unison with said printing mechanism and actuating said "pay-out" reel for advancing a length of ribbon to the "take-up" reel simultaneously with the passage of a piece of paper and a type plate through the 65 printing mechanism, and for taking back a different length of ribbon against the "pull" of said "take-up" reel after the passage of a piece of paper and type plate through the printing mechanism, said mech- 70 anism thereby advancing the ribbon progressively by successive fractional lengths from one of the reels to the other, and means automatically operable when a given total length of ribbon has passed through the 75 printing mechanism for altering the length relation of "pay-out" and "pull-back" to cause the ribbon to progress by successive fractional lengths to re-transfer it to its original holder. 80
11. A printing machine having a printing mechanism through which paper and type plates pass together, in combination with a "take-up" reel and a "pay-out" reel arranged one at each side of the printing 85 mechanism and having an inked ribbon extending therebetween and interposed between the paper and type plate, mechanism actuating said "take-up" reel and exerting a constant pull on the ribbon in the direction of movement of the paper and type plates, and other mechanism operating in timed relation to the printing operations and actuating said "pay-out" reel for advancing a length of ribbon to the "take-up" 90 reel simultaneously with the passage of a piece of paper and a type plate through the printing mechanism and at the same speed as the type plate and pieces of paper, and for taking back a different length of ribbon 95 against the "pull" of said "take-up" reel after the passage of a piece of paper and type plate through the printing mechanism, and at a different speed, said mechanisms thereby advancing the ribbon progressively 100 by successive fractional lengths in one direction, and means automatically operable when a given total length of ribbon has passed through the printing mechanism for changing the length relation of ribbon paid out 105 and pulled back to cause the ribbon to progress by successive fractional lengths in the opposite direction.
- In witness whereof, I have hereunto set my hand, this 22nd day of August, 1910, in 110 the presence of two subscribing witnesses.
